UNITED STATES PATENT OFFICE.

SAMUEL TRACHTENBERG, OF CLEVELAND, OHIO.

MECHANICAL FLAG-WAVING DEVICE.

Application filed April 10, 1922. Serial No. 551,415.

To all whom it may concern:

Be it known that I, SAMUEL TRACHTENBERG, a citizen of the United States, residing at Cleveland, in the county of Cuyahoga and State of Ohio, have invented certain new and useful Improvements in Mechanical Flag-Waving Devices, of which the following is a specification.

This invention is a mechanical device for causing a flag to wave, or to appear to wave, and is intended to be used for advertising purposes or to attract attention or under other conditions where an apparently waving flag is desired.

The movement of the flag is produced by a mechanical contrivance enclosed within a casing such as might be made by sewing the edges of two flags together, the mechanical parts being operated by a motor and connections from the motor extending through the flag staff.

The invention will be more fully understood by reference to the accompanying drawings in which Fig. 1 is a side elevation of the apparatus. Fig. 2 is a similar view, partly in section, the mechanical structure within the flag being exposed. Fig. 3 is a horizontal section on the line 3-3 of Fig. 2. Figs. 4 and 5 are similar views with the parts in different positions. Fig. 6 is a detail of the parts within the flag. Fig. 7 is a section on the line 7-7 of Fig. 2.

The flag, which is indicated at 8 in the drawings, conveniently consists of two flags sewed together at their upper, lower and outer edges, forming a casing which is open at its inner end so that it can be slipped over the hinged arms 11 and the supporting wires 12 as illustrated in Figs. 2, 3 and 4. The open end of the flag casing is provided with snap buttons 9 by means of which those ends are fastened to the staff 18, so that the operating mechanism is concealed within the flag casing.

This operating mechanism comprises a series of double hinged arms 11, comprising pairs of parallel plates which are hinged together at their ends as indicated at 11^a and 11^b. It will be noted that the hinges 11^a are attached to the meeting ends of the plates, on the outer sides, while the hinges 11^b are fastened internally or between the plates, one leaf of each of said hinges being fastened to the inside of one plate and the other leaf to the inside of the next oppo-

site plate, the relative arrangement of these internal hinges 11^b being reversed at alternate "elbows" or angles of the structure. The whole forms in effect a sort of double link arrangement which, when the parts are swung will cause them to bend at the hinges and so fold and unfold, as illustrated in Figs. 3, 4, and 5 to produce an alternate elongation and retraction of the flag, which of course is flexible to permit the action.

The flag casing is supported by a series of vertical rods 12, covered with rubber tubing 12' to prevent tearing the flag, and these rods 12 extend through and form the pintles of the hinges 11^a. The rods distend the flag and support the same in open position.

The inner arms 11 are fixed to an angular brace 14, the ends of which are secured to the staff 18 by rivets or otherwise.

A bell crank lever 16 is fulcrumed at 16^a on the brace 14 and one arm thereof is connected by a link 15 to one of the rear arms 11, and the other arm of the bell crank lever projects through a slot in the hollow flag staff 18 and is connected by a wire 17 and eye 19 to a crank 27 on a gear 26 which meshes with a pinion 25 geared by a gear wheel 24 to a gear 23 on the shaft of an electric motor 22, the gears being supported by a plate 28 fastened to the base 21, the constructions being such that as the motor shaft turns it will pull down on the wire 17 and rock the bell crank 16. A spring 20 connected between the bell crank and the bracket gives the reverse movement. The outer end or section of the structure within the flag is provided with a pair of small coiled springs 13 which assist in holding the flag distended in proper shape, at its outer end, these springs running to the outer corners of the flag casing.

In operation, the motor will as stated revolve the crank 27 which pulls down on the wire 17 and rocks the bell crank 16 which, by its connection to the arms 11 will swing said arms on their hinges and so cause them to bend or retract, and on the reverse motion the arms are swung in the opposite direction, causing the elongation or extension of the same and the flag carried thereby. This gives the appearance of the waving flag operated by mechanical means which are concealed within the flag and the staff.

I claim:

1. A flag waving device comprising a se-

ries of arms hinged together, a flag supported thereon, said flag having two opposite flexible sides between which the arms are enclosed, and means to swing said arms on their hinges.

2. A flag waving device comprising a series of pairs of arms connected in parallel relation by hinges at their ends, a flag supported on said arms, and means attached to 10 one pair of arms to swing the same, and means to communicate the motion of said pair to the other pairs successively.

3. A flag waving device comprising a flexible flag casing, a staff to which it is 15 attached, a series of hinged arms supported on the staff and enclosed within the casing, and means extending through the staff and connected to said arms to swing the latter on their hinges.

20 4. The combination of a hollow flag staff, a flexible flag casing attached thereto, a series of hinged arms supported on the staff and projecting outwardly within the casing, and means extending through the staff and 25 connected to said arms to swing the same on their hinges.

5. The combination of a hollow flag staff, a flexible flag casing attached thereto, a series of hinged arms supported on the staff 30 and projecting outwardly within the casing, and means extending through the staff and connected to said arms to swing the same on their hinges, and means carried by said arms to distend the flag casing.

6. The combination of a hollow flag staff, 35 a flexible flag casing attached thereto, a series of hinged arms supported on the staff and projecting outwardly within the casing, and means extending through the staff and connected to said arms to swing 40 the same on their hinges, and means carried by said arms to distend the flag casing, including rods projecting from the arms at the hinge joints thereof.

7. The combination with a hollow flag 45 staff and a flexible flag casing attached thereto, of means within the flag casing to flex the same, a bell crank supported on the staff and connected to said means, a rod connected to the crank and extending 50 through the hollow of the staff, and a motor connected to said rod to operate the same.

8. A flag waving device comprising a series of pairs of arms, the arms of each pair being arranged in parallel relation, hinges 55 connecting the respective arms of successive pairs, other hinges connecting the arms of each pair with the opposite arms of adjacent pairs, the flag being supported on said arms, and means to swing the arms on 60 their hinges, and means carried by the arms to distend the flag.

In testimony whereof, I affix my signature in presence of two witnesses.

SAMUEL TRACHTENBERG.
